DRAFT AND BUFFER GEAR

William M. Dwyer, Chicago, Ill., assignor to W. H. Miner, Inc., Chicago, Ill., a corporation of Delaware

Application July 12, 1933, Serial No. 680,046

7 Claims. (Cl. 213—9)

This invention relates to improvements in draft and buffer gears.

One object of the invention is to provide a simple and efficient combined draft and buffer gear, especially adapted for mine cars, comprising a buffer cap movable inwardly toward the car and a draft member movable away from the car, wherein shock absorbing means is employed to cushion both the draft and buffering shocks, the shock absorbing means being compressed between the buffer cap and draft member when a pulling action is applied to the latter, means being also employed to hold the buffer cap stationary during outward movement of the draft member of the combined gear, whereby the buffer cap acts as a fixed abutment for the shock absorbing means.

Another object of the invention is to provide, in a gear of the character described in the preceding paragraph, simple and efficient means for accurately guiding the draft member in a straight path, thereby eliminating binding of the parts of the gear.

A more specific object of the invention is to provide, in a combined draft and buffer gear including a buffering cap and a draft member, which are movable toward and away from each other, and wherein the pulling action is applied to the top of the draft member, simple and efficient means for accurately guiding the draft member in a straight-line path and holding the latter against tilting movement, thus eliminating binding of the parts of the gear.

Other objects of the invention will more clearly appear from the description and claims herein-after following.

In the drawing, forming a part of this specification, Figure 1 is a front elevational view of a portion of one end of a mine car, illustrating my improved draft and buffer gear in connection therewith, the gear being shown in end elevation with the buffer cap partly broken away to more clearly illustrate the internal structure of the gear. Figure 2 is a horizontal sectional view, corresponding substantially to the line 2—2 of Figure 1. And Figures 3 and 4 are vertical sectional views, corresponding respectively to the lines 3—3 and 4—4 of Figure 1, the coupling pin being shown in side elevation in Figure 3.

In said drawing, 10 indicates the end sill member of a mine car, which carries my improved draft and buffer gear. My improved gear comprises broadly a support A; a buffer cap B; a draft member C; a pair of buffering springs D—D;

and a pair of combined draft and buffering springs E—E.

The support A, which is preferably a casting, forms a housing for the other parts of the gear. The support A may be in the form of a separate member attached to the end sill of the car, or may be formed as a part of the end sill casting 10, as illustrated in the drawing. The support A has a vertical rear wall 11 which, as shown, forms a continuation of the casting 10. The wall 11 has forwardly projecting, vertical side flanges 12—12 forming the side walls of the housing A, and spaced horizontal top and bottom flanges 13 and 14 forming the top and bottom walls of said housing. The top wall 13 of the housing A has the midsection thereof upwardly offset, as clearly shown in Figures 1, 3, and 4, thereby providing spaced side wall sections 15—15 and a top wall section 16 connecting the upper ends of the sections 15—15. Adjacent to the offset section, the top wall 13 presents spaced ledges 17—17, which provide downwardly facing guide surfaces, which cooperate with the buffer cap B, as hereinafter more fully pointed out. The central section of the bottom wall 14 of the housing A is slightly downwardly offset, as shown in Figure 1 and indicated by 18. As most clearly shown in Figure 4, the bottom wall 14 is somewhat longer than the top wall 13 of the housing A, thereby presenting a supporting shelf on which the buffer cap B is guided. At opposite sides of the housing A, the top and bottom walls are provided with interior stop shoulders 19—19 and 19—19, which serve to limit the inward movement of the buffer cap B.

The buffer cap B has a rounded vertical front wall 20, which presents an outer buffering face cooperating with a similar buffer of the adjacent car. The cap B also has spaced vertical side walls 21—21 and horizontal top and bottom walls 22 and 23. The top wall 22 is somewhat shorter than the wall 23, as clearly shown in Figure 4. The midsection of the inner end portion of the bottom wall 23 is slotted, as indicated at 24 in Figure 3, to accommodate the lower end of the coupling pin, which is indicated by 25. Inwardly of the front wall 20, the buffer cap B is provided with a boxlike section 26, which has a flat upper guide surface 27 serving to support the front end portion of the draft member C. The guide surface 27 is depressed with respect to the upper surface of the buffer cap B, as clearly shown in Figures 1 and 3. The buffer cap B is telescoped within the housing A and is connected thereto by a pair of vertically disposed rivets 28—28 at opposite sides of the housing A extending through

openings in the top and bottom walls 13 and 14 of the housing and slots 29-29 in the top and bottom walls 22 and 23 of the buffer cap B. The rivets 28-28 act as stops to limit the outward movement of the buffing cap B.

The draft member C has a follower section 30 at the bottom thereof defined by a vertical rear wall 31, spaced top and bottom walls 32 and 33, and spaced side walls 34-34. The bottom wall 33 of the follower section 30 is disposed above the bottom wall 23 of the buffer cap B, as shown in Figure 4. The follower section 30 is also provided with a vertically disposed central web 35, which terminates in an enlargement 36 at the forward end adapted to receive the shank of the coupling pin 25. The major portion of the top wall 32 of the follower section 30 is of the width shown in Figure 4. At the center of the follower section 30, the top wall 32 is extended forwardly to provide a ledge 37, which rests on the guide surface 27 of the buffer cap B, as clearly shown in Figure 3. The enlargement 36 connects the bottom wall 33 of the follower section 30 to the ledge 37 and serves to brace the latter. The draft member C has a reduced, channel-shaped, central portion 38 extending upwardly from the follower section 30 thereof, the back wall of the channel-shaped portion forming a continuation of the wall 31. At the upper end, the draft member C is provided with a forwardly extending arm 39, through which the coupling pin 25 extends. The side flanges of the channel-shaped portion 38 form reinforcing webs connecting the arm 39, the wall 32, and the back wall of the portion 38. The usual coupling member, which may be in the form of a link, is accommodated between the arm 39 and the ledge 37 of the draft member C. The top wall 32 of the follower section 30 of the draft member C presents ledges 40-40 at opposite sides of the reduced section 38 of the draft member C, the ledges 40-40 cooperating with the ledges 17-17 of the housing A to accurately guide the draft member in a true horizontal path.

The buffing springs D-D are disposed at opposite sides of the mechanism and have their front and rear ends bearing respectively on the inner side of the front wall 20 of the buffer cap B and the wall 11 of the housing A.

The combined draft and buffing springs E-E are disposed between the springs D-D and have their opposite ends bearing respectively on the wall 31 of the follower section 30 and the inner side of the front wall 20 of the buffer cap B. The springs E-E are supported on the bottom wall 33 of the follower section 30, thus preventing binding of these springs while being compressed.

In a buffing action, the cap B is forced inwardly toward the end of the car, thereby compressing the springs D-D against the wall 11 of the housing A and compressing the springs E-E against the follower section 30 of the draft member C, the draft member being held stationary at this time by engagement with the wall 11 of the housing A. Inward movement of the buffing cap is limited by engagement of the inner ends of the top and bottom walls 22 and 23 with the stop shoulders 19-19 and 19-19 of the housing A.

When a pulling action is applied to the draft member C by means of a coupling link connected to the pin 25, the draft member is pulled outwardly away from the car, thereby compressing the springs E-E against the front wall 20 of the buffer cap B, the latter being at this time held stationary by the stop-acting rivets 28-28. The outward movement of the draft member is lim-

ited by engagement of the front edge of the wall 32 of the follower section 30 with the rear edge of the top wall 22 of the buffer cap B and by engagement of the enlargement 36 of the draft member C with the boxlike section 20 of the buffer cap B. The draft member is accurately guided in a straight-line horizontal path during its reciprocating movement by the interengaging guide means of the draft member C, the housing A, and the buffer cap B, the guide surface 27 of the cap B being practically in the same plane as the guide surfaces of the ledges 17-17 of the housing A. The ledge 37, together with the top wall 32 of the follower section 30 of the draft member C, forms in effect a slide which prevents tilting of the draft member C by engagement with the guide ledges 17-17 of the housing and the guide surface 27 of the buffing cap B. As the draft member C is prevented from tilting, there is no danger of the same binding between the walls of the housing due to the eccentric pulling action of the coupling link which is connected to the top part of the draft member.

I have herein shown and described what I now consider the preferred manner of carrying out my invention, but the same is merely illustrative and I contemplate all changes and modifications that come within the scope of the claims appended hereto.

I claim:

1. In a combined draft and buffer gear for cars, the combination with a housing at the end of the car; of a buffer cap slidably guided within the housing for movement toward and away from the end of the car, said buffer cap having a flat top surface; a draft member movable away from the end of the car, said draft member having a horizontal shelf provided with a depending bracing section, said section and shelf having aligned coupling pin-receiving openings, the outer end of said shelf being slidably guided on the flat top surface of the buffer cap; downwardly facing guide means on the housing engaging the top of said shelf; and shock absorbing means yieldingly opposing movement of the buffer cap and draft member.

2. In a combined draft and buffer gear for cars, the combination with a housing at the end of the car; of a buffer cap slidably guided within said housing for movement toward the end of the car, said cap having a flat top surface; guide means on the housing having downwardly facing, horizontal, guide surfaces, said guide surfaces being disposed above said top surface of the cap; a draft member movable away from the end of the car, said draft member having a vertically disposed follower section, a horizontally disposed plate member forwardly extending from said follower section, a vertical central web below said plate member reinforcing said draft member, and an enlargement at the outer end of said web, said enlargement and plate member having aligned coupling pin-receiving openings, said plate member having oppositely facing, guide faces respectively engaging the guide surfaces of the buffer cap and housing; and shock absorbing means yieldingly opposing movement of the buffer cap and draft member.

3. In a combined draft and buffer gear for cars, the combination with a housing at the end of the car; of a buffer cap slidably guided in said housing; a guide member on said housing above said cap, said guide member having a horizontal, downwardly facing, guide surface thereon; a draft member, said draft member slidably engaging the

guide surfaces of the housing; a forwardly projecting ledge on the draft member, said ledge being slidingly supported on the top of the buffer cap; a forwardly extending reinforcement on said follower below said ledge; a forwardly projecting arm on said draft member above said ledge, said arm and reinforcement having vertically aligned coupling pin-receiving openings; and shock absorbing means yieldingly opposing movement of the buffer cap and draft member.

4. In a combined draft and buffer gear for cars, the combination with a housing at the end of the car, said housing having top and bottom walls and downwardly facing, horizontal guide ledges between said top and bottom walls; of a draft member between said top and bottom walls, said draft member having top and bottom sections and upwardly facing guide ledges between said sections engaging the ledges of the housing, said draft member also having a forwardly extending guide shelf having a bottom guide surface disposed below said guide ledges; a depending boss on said shelf; a coupling pin extending through said boss and said top section of said draft member; a buffer cap guided on the bottom wall of the housing, said cap having a top guide surface engaging said guide surface of the shelf; and shock absorbing means interposed between said buffer cap and the bottom section of said draft member.

5. In a combined draft and buffer gear for cars, the combination with a housing having a bottom wall and horizontal guide ledges above said bottom wall, said ledges having downwardly facing guide surfaces; of a buffer cap below said guide ledges, said cap being slidingly supported on the bottom wall of the housing, said cap having an upwardly facing top guide surface; a draft member having a follower section opposed to the buffer cap; a vertically disposed reinforcing boss on said draft member forwardly of said follower section said draft member having upwardly facing guide sur-

faces engaging the guide ledges of the housing; a forwardly projecting guide arm extending from the top of said boss and forming an integral part of said draft member, said arm being slidingly supported on the guide surface of the buffer cap; a coupling pin connected to said draft member above the guide surfaces of said member and extending into said boss; and shock absorbing means interposed between the buffer cap and the follower section of the draft member.

5

6. In a draft gear for cars, the combination with a housing; of a draft member having a horizontally disposed guide means thereon in the form of a plate section; guide means on the housing engaging above and below said plate section; a cylindrical reinforcement depending from said plate section, said reinforcement and plate section having aligned coupling pin-receiving openings; and shock absorbing means yieldingly opposing outward movement of the draft member.

10

7. In a combined draft and buffer gear for cars, the combination with a housing; of a buffer cap movable inwardly of said housing; a draft member having a vertically disposed follower section; a horizontally disposed forwardly projecting plate on said follower section, between the top and bottom thereof; a forwardly projecting arm above said plate; a horizontal bottom web below said plate; a vertical reinforcing member spaced forwardly from said follower section connecting said plate and web; a vertical reinforcing web connecting said reinforcing member, plate, bottom web and follower section, said arm, plate and reinforcing member having vertically aligned coupling pin-receiving openings, and the outer end of said plate being slidingly supported on said cap; cushioning means opposing relative movement of said cap and draft member, said cushioning means bearing on said follower section; and guide means on said housing engaging said plate from above.
